COLLAPSIBLE PUNCH

Josephus J. Thayer, Battle Creek, Mich., assignor
to General Foods Corporation, New York, N. Y.,
a corporation of Delaware

Application January 7, 1943, Serial No. 471,609

12 Claims. (Cl. 164—124)

This invention relates to punches for forming articles from suitable blank material, such as metal, cardboard, etc., and more particularly to punches which can be collapsed to release the formed articles.

One of the problems in making such articles by a punch and die operation is to free the completed article from the punch, particularly when it is formed with interior threads or other projections. For purposes of illustration, the invention will accordingly be described hereinafter with reference to the forming of interiorly threaded caps for bottles or jars, etc., but it will be understood that the invention is useful in connection with the formation of any article which is not freely released by the punch. Collapsible punches have been proposed heretofore for such operations, but it is difficult to provide a simple and practical punch structure which is readily and quickly collapsible as required in commercial production and yet at the same time is capable of withstanding the substantial compressive stresses to which it is subjected in the formation of the caps. Hence in actual practice threaded caps are usually removed from the punch by mechanical devices which engage each cap and rotate it to spin it off the punch.

The principal objects of the present invention are to provide a novel collapsible punch which is of simple but durable construction, which can be readily and practically instantaneously collapsed to free the cap, and which at the same time is strong and rigid when expanded to withstand the substantial compressive stresses necessary to form the cap.

Other objects will appear more fully hereinafter as the description of the invention proceeds.

One embodiment of the invention has been illustrated in the accompanying drawings, but it is to be expressly understood that said drawings are for purposes of illustration only and are not to be taken as a definition of the limits of the invention, reference being had to the appended claims for this purpose.

In the drawings:

Fig. 1 is an elevation of a punch embodying the invention, together with associated operating mechanism;

Fig. 2 is a section on the line 2—2 of Fig. 1;

Fig. 3 is a section on the line 3—3 of Fig. 1;

Fig. 4 is a section on the line 4—4 of Fig. 1;

Fig. 5 is a section on the line 5—5 of Fig. 1;

Fig. 6 is an enlarged sectional view corresponding to the lower part of Fig. 2, but with the punch head collapsed;

Fig. 7 is a section on the line 7—7 of Fig. 6;
Fig. 8 is an enlarged view of the punch head, with a formed cap thereon;

Fig. 9 is a detail view of the cap itself;

5 Figs. 10 and 11 show the arrangement of the elements forming the punch head, Fig. 10 being a section on the line 10—10 of Fig. 1 and Fig. 11 being a bottom plan; and

Figs. 12 and 13 are diagrammatic views illustrating the collapse of the punch head.

A suitable punch head adapted to form an interiorly threaded cap of cardboard or like fibrous material is shown in Figs. 1 and 2 and enlarged in Fig. 8. The cap material may suitably comprise an outer layer 1 of fairly stiff cardboard and an inner layer 2 of relatively spongy material adapted to be compressed into a thread by virtue of the spiral groove 3 of the punch head. The cap blank 4 is positioned over the die opening 5

10 (Fig. 1) and the punch is moved into and out of the die in any suitable manner, as by mounting it on the vertically movable cross head of a punch press, part of which is shown at 6 in Figs. 1 and 2. The blank is drawn into cap-shape and the interior thread formed on downward movement of the punch, and if a continuous web or strip of blank material is used, it is pinched off between the shoulder 7 of the punch and the edge of the die opening. The punch is then withdrawn from the die, carrying with it the formed cap, and is collapsed as hereinafter described to release the cap. It will be understood, however, that the use of the invention is not restricted to forming caps of this particular type or material or to this

15 particular method of operation.

20 The preferred arrangement of the several elements forming the collapsible punch head are shown in detail in Figs. 8, 10 and 11. These elements are four in number, comprising two pairs of elements 8 and 9 respectively, the elements of each pair being alike but diametrically opposite. The outer surfaces of these elements are curved on a common radius so that, when expanded as shown in Figs. 10 and 11, they form a substantially continuous circular periphery for the punch head. The elements 8 are in effect wedge-shaped, the sides 10 of each of these elements extending inwardly from the ends of its curved periphery and diverging from one another. The elements 9 are provided with correspondingly inclined surfaces 11, and preferably the surfaces 10 and 11 are in tight engagement when the punch head is expanded.

25 As hereinafter described, the elements of each pair are movable inwardly toward each other

30 and are held in this collapsed position by a suitable lock mechanism.

35 The preferred lock mechanism is shown in detail in Figs. 10 and 11. It consists of a pair of plates 12 and 13 which are held in close proximity by a pair of springs 14 and 15. The plates 12 and 13 are provided with a series of notches 16 and 17 respectively, and the ends of the springs 14 and 15 are received in these notches.

40 The plates 12 and 13 are provided with a series of notches 16 and 17 respectively, and the ends of the springs 14 and 15 are received in these notches.

45 The plates 12 and 13 are provided with a series of notches 16 and 17 respectively, and the ends of the springs 14 and 15 are received in these notches.

50 The plates 12 and 13 are provided with a series of notches 16 and 17 respectively, and the ends of the springs 14 and 15 are received in these notches.

55 The plates 12 and 13 are provided with a series of notches 16 and 17 respectively, and the ends of the springs 14 and 15 are received in these notches.

along their common diameter. Owing to the inclination of the surfaces 10 and 11, inward movement of the elements 8 to the position shown in Fig. 12 results in separation of these surfaces so that the elements 9 may then move inwardly to the position shown in Fig. 13. During this movement the tips 12 of the elements 9 move along chords of the expanded punch head circle and thus are withdrawn within its circumference. It will be understood that Figs. 12 and 13 are diagrammatic views illustrating the collapsing operation and that it is not necessary for the elements 8 to be moved completely inwardly before the elements 9 are moved inwardly, as the movement of the latter may start immediately after initial displacement of the former and both collapsing movements thereafter continue simultaneously.

In order to provide for the collapsing movement described above, the punch head elements 8 and 9 are each carried by supporting members which are pivoted on the body of the punch, the rocking movement of these supports about their pivots causing the inward and outward movement of the punch head elements. To accommodate these pivoted supporting members while at the same time housing them within the circular exterior of the punch, the body of the punch is preferably provided with longitudinally extending radial slots in which the supports operate. This construction is preferably obtained (Fig. 5) by forming the body of the punch of four similar parts 13 each forming one quadrant of the punch body, said parts being spaced from one another to provide four longitudinally extending diametrically opposite slots intersecting to provide a central opening through the punch body. The body parts 13 may have any suitable external shape and may be assembled and mounted in any suitable manner. In the form shown, each body part is square in cross section except at its lower portion 14 which is rounded to form a circular punch body capable of entering the die opening 5. The body parts 13 are suitably mounted on the cross head 6 by means of a supporting plate 15 secured to the cross head by bolts 16, the body parts being secured to this plate by studs 17. To aid in centering and aligning the punch body, the upper end of each body part 13 is provided with one quadrant of a raised annular rib 18 engaging an annular groove 19 in the lower face of the supporting plate 15.

The pairs of punch head elements 8 and 9 are carried by corresponding pairs of pivoted supporting members 20 and 21, each of which is pivoted in any suitable manner in one of the longitudinal slots in the punch body. As herein shown, the supports 20 are carried by pivot pins 22 and the supports 21 by pivot pins 23, these pivot pins being disposed at different elevations as shown in Figs. 6 and 7 and each extending through two of the punch body parts 13.

The supports 20 and 21 are thus free to rock about their pivots so as to move the punch head elements 8 and 9 inwardly from expanded position. Preferably this movement is effected and controlled by means of an operating member 24 slidably longitudinally in the central opening in the punch body and adapted to engage and spread the inner ends of the supports. Referring particularly to Figs. 6 and 7, these supports terminate in rounded heads 25 and 26, which may if desired extend into or through slots in the supporting plate 15 which are aligned with the slots in the punch body. The heads 25 and 26 are

engaged respectively by cam surfaces 27 and 28, when the operating member 24 is retracted or withdrawn into the punch body, so as to spread or separate the inner ends of the supports and thus move the punch head elements 8 and 9 inwardly as described above with reference to Figs. 12 and 13. It will be understood that the cam surfaces are arranged so that the inward movement of the punch head elements 8 begins slightly ahead of the inward movement of the punch head elements 9, but so that the collapse of the punch head takes place substantially instantaneously.

When the operating member 24 is moved in the opposite direction, its outer end engages inclined cam surfaces 29 of the punch head elements 8 and similar inclined cam surfaces 30 of the punch head elements 9 to move these elements outwardly to expanded position, the cam surfaces 27 and 28 being simultaneously withdrawn from engagement with the heads 25 and 26 of the rocking supports. Further outward movement of the operating member projects its outer end between the punch head elements as shown in Figs. 10 and 11, the dimensions of the operating member and of the cam projections 29 and 30 preferably being such that the expanded punch head is solid along diameters at right angles. The outward movement of the punch head elements may be limited by the engagement of the heads 25 and 26 of the supports with the surfaces of the operating member 24.

It will be seen that the operating member 24 has a substantially rectangular cross section, but that its thickness in either direction varies at different points along its length. Accordingly the bar has a basic cross sectional shape and area corresponding to the central hole through the punch body which is defined by the inner rectangular corners of the body parts 13, with the raised cam surfaces, etc., of varying height projecting into the slots between these parts as shown in Fig. 5. Preferably the raised surfaces extend the full width of the slots and thus guide the longitudinal movement of the operating member, the latter having in effect rectangular guide grooves along each corner which slide on the inner rectangular corners of the body parts 13.

Any suitable means may be employed for operating the member 24 in timed relation with the operation of the cross head 6, but preferably it is retracted pneumatically to release the formed cap, in which case it may conveniently be returned to expand the punch head by resilient means compressed during its movement of retraction. To these ends, the operating member 24 is made round in cross section to pass slidably through a bushing 31 and into a pneumatic cylinder 32. This cylinder 32, as shown, is housed in a recess in the cross head and mounted on the supporting plate 15 by means of bolts 33, spacers 34 separating the cylinder from the plate and providing space for the heads of the bolts 17. Within the cylinder 32, the operating rod 24 carries a piston 35 which is secured by washers 36 and 37 between a shoulder 38 on the operating rod and a nut 39 on its end. Air under pressure is admitted to the cylinder beneath the piston by a passage 40, and the upward stroke of the piston is limited in any suitable manner as by means of an annular retaining member 41 secured to the cylinder 32 by means of screws 42. Upward movement of the operating rod 24 serves to compress a return spring 43 housed in a sleeve 44 secured to the cross head 6 by means of screws 45, the

upper end of the spring bearing against an adjusting screw 46 threaded in a plate 47 which is secured to the sleeve 44 by the bolts 45. The return stroke of the operating member is limited by engagement of the washer 36 with the bushing 31.

The operation of the apparatus will be understood from the foregoing description, and can be summarized as follows. With the punch head in expanded position and the parts as shown in Fig. 1, the cross head 6 descends and the punch enters the die opening 5 and forms the threaded cap shown in Fig. 9. The cross head then ascends, raising the punch out of the die opening and carrying with it the formed cap. After the end of the punch has cleared the die, air under pressure is admitted to the cylinder 32, retracting the operating rod 24 and collapsing the punch head to release the cap. This operation takes place very rapidly, and at the same time the spring 43 is compressed so that as soon as the air pressure is cut off, the operating rod 24 is snapped back to its outermost position, expanding the punch head for the next forming stroke. The construction is very simple and comprises few parts, but its operation is practically instantaneous and at the same time a strong rigid punch head is provided which is capable of withstanding the substantial pressures to which it is subjected in the forming operation.

While only one embodiment of the invention has been described and illustrated in the drawings, it is to be expressly understood that this embodiment is for purposes of illustration only, and that various changes can be made in the form, details of construction and arrangement of the parts without departing from the spirit of the invention, many of which changes will now occur to those skilled in the art. Accordingly reference is to be had to the appended claims for a definition of the limits of the invention.

What is claimed is:

1. A collapsible punch comprising a plurality of elements forming a punch head of the desired shape when in expanded position, supports for said elements each extending longitudinally of and pivoted intermediate its ends on the punch, whereby said elements are movable inwardly and outwardly between expanded and collapsed positions, a member extending centrally through said punch and movable longitudinally therein, said member on movement in one direction rocking said supports about their pivots to move said elements to expanded position and on movement in the other direction rocking said supports about their pivots to move said elements to collapsed position, pneumatic means for moving said member in said second direction, and resilient means stressed by movement of said member in said second direction for returning said member in said first direction.

2. A collapsible punch comprising two pairs of oppositely disposed elements forming a punch head of the desired shape when in expanded position, said elements being carried by corresponding pairs of supports each extending longitudinally of the punch and pivoted intermediate its ends thereto, an actuating member substantially rectangular in cross section extending centrally through said punch and longitudinally movable therein, each surface of said member being shaped to engage one of said supports inwardly of its pivot on retraction of said member to move said elements to collapsed position, and said member engaging said supports outwardly of their pivots on movement in the opposite direction to move

said elements to expanded position, pneumatic means for retracting said member, and resilient means stressed by retraction of said member for moving it in said opposite direction.

3. A collapsible punch comprising two pairs of oppositely disposed elements forming a punch head of the desired shape when in expanded position, said elements being carried by corresponding pairs of supports each extending longitudinally of the punch and pivoted intermediate its ends thereto, an actuating member substantially rectangular in cross section extending centrally through said punch and movable longitudinally therein, said member in its outermost position separating and maintaining said elements in expanded position with the inner ends of said supports engaging said member, said member also having raised surfaces adapted on retraction thereof to engage said inner ends and move said elements to collapse the punch head, pneumatic means for retracting said member, and resilient means stressed by retraction of said member for moving it in the opposite direction.

4. A collapsible punch head comprising two pairs of oppositely disposed elements forming a punch head of the desired shape when in expanded position, a punch body comprising four quadrantal parts spaced from one another to provide longitudinal slots in the sides of the punch with the intersection thereof forming a central opening, said elements being carried by corresponding pairs of supports each pivoted intermediate its ends in one of said slots, an actuating member movable longitudinally in said opening, the surfaces of said member being shaped to engage said supports inwardly of their pivots on retraction of said member and to move said elements and collapse the punch head, and said member engaging said supports outwardly of their pivots on movement in the opposite direction to move said elements and expand the punch head, pneumatic means for moving said member in said one direction, and resilient means stressed by movement of said member in said one direction for moving it in said opposite direction.

5. A collapsible punch comprising a punch body, two pairs of supports pivoted on said body the ends of which carry elements forming in expanded position a substantially circular punch head, each element of one pair of diametrically opposite elements having outwardly tapering surfaces adapted to cooperate with adjacent outwardly tapering surfaces of the elements of the other pair to form a substantially continuous periphery, a central actuating member the end of which is adapted to be advanced between said pairs of elements when expanded, the diametrical dimensions of said member along the two diameters corresponding to said pairs of elements being such that the expanded punch head is solidly held along both said diameters, and means for moving said member longitudinally of the punch to advance said end relative to said elements as the punch head is expanded and to retract said member and collapse the punch head.

6. A collapsible punch comprising a punch body, two pairs of supports pivoted on said body the ends of which carry elements forming in expanded position a substantially circular punch head, each element of one pair of diametrically opposite elements having outwardly tapering surfaces adapted to cooperate with adjacent outwardly tapering surfaces of the elements of the other pair to form a substantially continuous periphery, a central actuating member the end of which is adapted to be advanced between said pairs of ele-

ments when expanded, the diametrical dimensions of said member along the two diameters corresponding to said pairs of elements being such that the expanded punch head is solidly held along both said diameters, means for advancing said member with said end camming said elements to expanded position as it advances between them, and means for moving said member in the opposite direction and collapsing said punch head.

7. A collapsible punch comprising a punch body, two pairs of supports pivoted on said body the ends of which carry elements forming in expanded position a substantially circular punch head, each element of one pair of diametrically opposite elements having outwardly tapering surfaces adapted to cooperate with adjacent outwardly tapering surfaces of the elements of the other pair to form a substantially continuous periphery, a central actuating member the end of which is adapted to be advanced between said pairs of elements when expanded, the diametrical dimensions of said member along the two diameters corresponding to said pairs of elements being such that the expanded punch head is solidly held along both said diameters, means for expanding said elements and advancing the end of said member between them, means for moving said member in the opposite direction to engage and spread said supports above their pivots, thereby collapsing the punch head.

8. A collapsible punch comprising a punch body, two pairs of supports pivoted on said body the ends of which carry elements forming in expanded position a substantially circular punch head, each element of one pair of diametrically opposite elements having outwardly tapering surfaces adapted to cooperate with adjacent outwardly tapering surfaces of the elements of the other pair to form a substantially continuous periphery, a central actuating member the end of which is adapted to be advanced between said pairs of elements when expanded, the diametrical dimensions of said member along the two diameters corresponding to said pairs of elements being such that the expanded punch head is solidly held along both said diameters, means for expanding said elements and advancing the end of said member between them, means for moving said member in the opposite direction to engage and spread said supports above their pivots to collapse said punch head, said member initiating inward movement of said one pair of elements before that of said other pair of elements.

9. A collapsible punch comprising a punch body, two pairs of supports pivoted on said body the ends of which carry elements forming in expanded position a substantially circular punch head, each element of one pair of diametrically opposite elements having outwardly tapering surfaces adapted to cooperate with adjacent outwardly tapering surfaces of the elements of the other pair to form a substantially continuous periphery, a central actuating member the end of which is adapted to be advanced between said pairs of elements when expanded, the diametrical dimensions of said member along the two diameters corresponding to said pairs of elements being such that the expanded punch head is solidly held along both said diameters, means for expanding said elements and advancing the end of said member between them, means for moving said member in the opposite direction to engage

5 gage and spread said supports above their pivots to collapse said punch head, said member initiating inward movement of said one pair of elements before that of said other pair of elements, and the inward movement of said one pair of elements being more rapid than that of said other pair of elements.

10. A collapsible punch comprising a punch body, two pairs of levers pivoted on said body each of which carries a punch head element at its outer end, said elements forming in expanded position a substantially circular punch head, each element of one pair of diametrically opposite elements having outwardly tapering surfaces adapted to cooperate with adjacent outwardly tapering surfaces of the elements of the other pair to form a substantially continuous periphery, a central actuating member movable longitudinally relative to the punch, means for expanding the punch head on outward movement of said member, and cam means on said member adapted on inward movement thereof to engage said levers above said pivots and collapse the punch head, the cams and lever arms being proportioned to cause more rapid inward movement of said one pair of elements than of said other pair of elements.

11. A collapsible punch comprising a punch body, two pairs of levers pivoted on said body each of which carries a punch head element at its outer end, said elements forming in expanded position a substantially circular punch head, each element of one pair of diametrically opposite elements having outwardly tapering surfaces adapted to cooperate with adjacent outwardly tapering surfaces of the elements of the other pair to form a substantially continuous periphery, a central actuating member movable longitudinally relative to the punch, means for expanding the punch head on outward movement of said member and said member being adapted on inward movement to engage said levers in a plane above their pivots and spread them substantially equal amounts to collapse the punch head, the pivots of the levers carrying said one pair of elements being at a greater distance from the punch head than the pivots of said other pair of punch elements.

12. A collapsible punch comprising a punch body, two pairs of levers pivoted on said body each of which carries a punch head element at its outer end, said elements forming in expanded position a substantially circular punch head, each element of one pair of diametrically opposite elements having outwardly tapering surfaces adapted to cooperate with adjacent outwardly tapering surfaces of the elements of the other pair to form a substantially continuous periphery, a central actuating member movable longitudinally relative to the punch, cam means on said member adapted on inward movement thereof to engage said levers above said pivots and collapse the punch head, the cams and lever arms being proportioned to cause more rapid inward movement of said one pair of elements than of said other pair of elements, and cam means adapted to expand said punch head on outward movement of said member and arranged to cause more rapid outward movement of said one pair of elements than of said other pair of elements.
